CLAIM

I claim the ornamental design for a plant clip, as shown and described.

DESCRIPTION

FIG. 1 is a perspective view of the plant clip in a closed position in use with a plant and a support wire.

FIG. 2 is a front elevational view of the plant clip.

FIG. 3 is a rear elevational view of the plant clip.

FIG. 4 is a left side elevational view of the plant clip.

FIG. 5 is a right side elevational view of the plant clip; and, FIG. 6 is a top plan view of the plant clip in an open position, the bottom plan view being a mirror image.

Broken lines illustrate features or environmental components that are not part of the design sought to be patented.
